UNITED STATES PATENT OFFICE.

ROBERT FINSTER AND PERCY WILSON, OF ERIE, PENNSYLVANIA, ASSIGNEES TO
HAMMERMILL PAPER COMPANY, OF ERIE, PENNSYLVANIA, A CORPORATION OF
PENNSYLVANIA.

PAPER-SORTING MACHINE.

1,302,466.

Specification of Letters Patent. Patented Apr. 29, 1919.

Application filed November 4, 1918. Serial No. 261,110.

To all whom it may concern:

Be it known that we, ROBERT FINSTER and PERCY WILSON, citizens of the United States, residing at Erie, in the county of Erie and 5 State of Pennsylvania, have jointly invented certain new and useful Improvements in Paper-Sorting Machines; and we do hereby declare the following to be a full, clear, and exact description of the invention, such as 10 will enable others skilled in the art to which it appertains to make and use the same, reference being had to the accompanying drawing, and to the letters of reference marked thereon, forming part of this specification. 15 Our invention relates to paper sorting machines and has for its object the construction of a machine whereby sheets of paper can be readily inspected for defects and delivered into different receptacles according 20 to the perfection existing in the sheets.

To accomplish this result we have devised a machine in which the paper sheets are delivered to traveling carrier tapes and during its traverse over the tapes the operator can 25 inspect it and speedily detect defects in the sheet, and at the end of such traverse there is provided manually operated deflectors, whereby the further travel of the sheet may be deflected into one path or another as said 30 inspection has shown to be necessary; and beyond these deflectors suitable rolls and tape carrier mechanism are provided to carry the sheets along the paths to which they have been deflected, and deposit them 35 in suitable receptacles provided therefor. For aiding the operator to more speedily detect defects in the sheets passing over the tapes, we preferably provide our device with an illuminating device consisting substan- 40 tially of suitable lights located under the path of the sheet as it moves forward.

The features of our invention are herein- 45 after fully set forth and described, and dia- grammatically illustrated in the accompany- ing drawing in which:—

The figure is a diagrammatic side view in elevation illustrating the features of our invention.

In the drawing the carrier tape mechanism 50 A and A², and their driving rolls A', A³ and A⁴, are of the usual type and operated in the usual manner as are such tapes and rolls in the common type in sheet conveying machines, ruling machines and other ma- 55 chines of that character, and are simply uti-

lized in combination with the features of our invention hereinafter described.

As shown diagrammatically, the tapes A lead from sheet delivery mechanism of any of the usual types (not shown) adapted to 60 deliver sheets one at a time to said tapes, and preferably spaced a short distance therefrom and in line therewith there is a second set of conveyer tapes A², supported on rolls A³ and A⁴, and preferably between the rolls 65 A' and A³ there is a reflecting mechanism F provided with suitable lights F', and on top of this reflector there is a plate of glass f in line with the carrying surface of the tapes A and A², the reflector F operating 70 to throw a strong light from the lights F' upon the under surface of the sheet passing over the glass F so that the operator can quickly detect any defects in such sheet; the mechanism can, however, if desired, be used 75 without the lights F' with good results.

Between the roll A⁴ and the rolls C, C², and the rolls E, E², there are mounted hinged deflectors H and I. These deflectors H and I normally lie in a horizontal position, as illustrated in full lines in the drawing, and when in that position a sheet passes from the tapes A on through and on to the carrier tapes B, B' and is by them delivered into the receptacle 1. 85

These deflectors H and I are provided at their ends with pins h and i, which extend outwardly so as to be engaged by arms J, J', on a hand lever K mounted at its lower end on a bearing L and adapted to be rocked right and left thereon. Under the deflector H there are sheet guides m, m', leading to the carrier tapes D, D', adapted to direct 90 sheets deflected by the deflector H to said carrier tapes, by which such sheets are con- 95 veyed to receptacle 2.

Under the deflector I there are sheet guides N adapted to direct sheets deflected by the end deflector I downward into a waste pile, (not shown). The carrier tape mech- 100 anism B, B', and its supporting roll mech- anism C, C', C², C³, the receptacle 1 for re- ceiving sheets delivered by the carrier tapes B, B', the carrier tape mechanism D, D', and its supporting roll mechanism E, E', 105 E², E³, and the receptacle 2 for receiving sheets delivered by the carrier tape mech- anism D, D', are of the usual and common type used and operated in sheet conveying machines, such as ruling machines and ma- 110

chines of that character, and the rolls and tapes are driven in the usual manner in such machines, and therefore further description of their construction and operation 5 is considered unnecessary.

In operation the lever stands normally in a vertical position as shown in full lines in the drawing; the deflectors H and I are then in their normal horizontal positions, 10 and sheets from the carrier tapes A pass over them to the carrier tapes B, B'; when, however, the operator discovers slight imperfections in a sheet as it is conveyed by the tapes A, he at once moves the lever K to the 15 left, which operates to raise the front edge of the deflector H and deflects such sheet downward between the guides m, m', to the carrier tapes D, D', by which it is delivered in receptacle 2. If, however, the sheet as it 20 passes over the tapes A, is shown to be more seriously defective, then the lever K is moved to the right, which operates to raise the front edge of the deflector I above the path of travel of the approaching sheet, and 25 deflects such sheet downward against the guide N, and to the waste, not shown.

It is believed from that from the foregoing description of the features of our invention and its operation, that others conversant with the art can fully understand and utilize the same; therefore what we claim as new and desire to secure by Letters-Patent is:—

1. In a sheet sorting mechanism comprising spaced tapes adapted to carry sheets, 35 two deflectors, one behind the other adjacent to the delivery end of said carrier-tape mechanism, an oscillating lever, arms thereon for engaging and operating said deflectors, and duplicate carrier tape mechanism adjacent to the rear side of said deflectors, one of which is adapted to continue the travel of the sheet in a continuous direction, and the other in a deflected direction, substantially as set forth.

2. In a sheet sorting machine, comprising spaced tapes adapted to receive and convey sheets of paper thereon, lighting mechanism between said carrier tape mechanism, a mov-

able sheet deflecting device for changing the 50 line of travel of the sheet adjacent to the delivery end of said carrier tape mechanism, and means for operating said deflector, substantially as set forth.

3. In a sheet sorting mechanism, comprising spaced tapes adapted to convey sheets, 55 movable deflectors adjacent to the delivery end of said carrier tape mechanism, a manually operative lever for operating one of said deflectors at a time, carrier tape mechanism 60 at the rear side of said deflectors adapted to receive and continue the travel of the sheet either in its direct or deflected line of travel, substantially as set forth.

4. In a sheet sorting mechanism, comprising spaced tapes adapted to receive and convey sheets of paper thereon, a lighting mechanism between said carrier tape mechanism, a reflector under said lighting mechanism for directing the light against the under surface of sheets passing over said carrier tape mechanism, a deflector adjacent to the delivery end of said carrier tape mechanism, a manually operated lever at one side 70 of the machine adapted to engage and operate 75 said deflector, substantially as set forth.

5. In a sheet sorting machine, comprising spaced tapes adapted to receive and convey sheets of paper thereon, a lighting mechanism between said carrier tape mechanism, 80 duplicate movable deflecting devices adjacent to the delivery end of said carrier tape mechanism, a manually operative lever adapted to operate one of said deflecting 85 devices at a time to change the line of travel of the sheets into one of two paths of travel, carrier tape mechanism to convey the sheets either in their direct line of travel, or in 90 their deflected line of travel, and receptacles at the delivery ends of said carrier tape mechanism to receive sheets delivered therefrom, substantially as set forth.

In testimony whereof we affix our signatures.

ROBERT FINSTER.
PERCY WILSON.
